UNITED STATES PATENT OFFICE.

JOSEPH D. HOLMES, OF NEW YORK, N. Y.

DESIGN FOR A STAND.

59,007.

Specification for Design. Patented Sept. 13, 1921.

Application filed January 15, 1921. Serial No. 437,600. Term of patent 7 years.

To all whom it may concern:

Be it known that I, JOSEPH D. HOLMES, a citizen of the United States, residing at New York, borough of Manhattan, in the county and State of New York, have invented a new, original, and ornamental Design for a Stand, of which the following is a specification, reference being had to the accompanying drawing, forming a part thereof.

Fig. 2 is a view in side elevation thereof.

I claim:

The ornamental design for a stand, as shown.

JOSEPH D. HOLMES.
